S. HOLICK

AIR VALVE FOR INNER TUBES

Filed July 14, 1921

Patented May 22, 1923.

1,456,444

UNITED STATES PATENT OFFICE.

STEVEN HOLICK, OF MILLSBORO, PENNSYLVANIA.

AIR VALVE FOR INNER TUBES.

Application filed July 14, 1921. Serial No. 484,653.

To all whom it may concern:

Be it known that I, STEVEN HOLICK, a citizen of the United States, residing at Millsboro, in the county of Washington and State of Pennsylvania, have invented certain new and useful Improvements in an Air Valve for Inner Tubes; and I do hereby declare the following to be a full, clear, and exact description of the invention, such as will enable others skilled in the art to which it appertains to make and use the same.

The invention relates to valves of the type designed particularly for the inner tubes of pneumatic tires and which embody a tubular stem and valve mechanism therein, automatic in action when inflating the tube and adapted to be operated at will for relieving internal pressure when required for any purpose.

The present invention provides a valve of the general nature hereinbefore indicated embodying a few number of parts, simple in structure and not liable to leak or otherwise get out of repair.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the nature of the invention.

Referring to the accompanying drawing forming a part of the specification,

Figure 1 is a vertical central longitudinal section of a valve of the nature herein indicated embodying the invention.

Figure 2 is a detail view of the plunger and cooperating guide therefor.

Figure 3 is a detail view of the inner end of the valve.

Corresponding and like parts are referred to in the following description and designated in the several views of the drawing by like reference characters.

The valve comprises the tubular stem 1 which is formed with a central opening having its outer portion enlarged to form an inner shoulder 2. A head 3 is provided at the inner end of the stem 1 to form an element for clamping the inner tube or other like part in a manner well understood. A valve 4 is located at the inner end of the

stem 1 and preferably consists of a flat piece of rubber or like flexible and resilient material suitable for the purpose. The valve 4 is of the flap variety and is secured at one end as indicated at 5. A plate 6 is placed against the outer side of the valve 4 and is retained in place by means of the fastening 5. The plate 6 has a central opening through which the point or extremity of a finger 7 passes and which finger is likewise retained in position by means of the fastening 5.

The plunger 8 extends through the opening of the tubular stem 1 and its inner end engages the valve 4 and its outer end projects slightly beyond the stem 1 to be pressed upon when it is required to unseat the valve 4 to relieve the internal pressure of the tube or other like part. A stop 9 is provided on the plunger 8 near the outer end thereof and operates to limit the outward movement of the plunger and to form an abutment for a spring 10 which is mounted on the plunger and has its inner end in engagement with the shoulder 2. A guide 11 is threaded in the outer enlarged portion of the opening formed in the stem 1 and its inner end cooperates with the stop 9 to limit the outward movement of the plunger and is adapted to 75 cooperate with the stop 9 to prevent loss of compression and thereby cooperate in conjunction with the valve 4 or independently thereof.

It will be understood that the part 9 also performs the function of a valve and the inner end of the guide 11 constitutes a seat for the part 9 to close against. When air is passing through the stem 1 the part 9 is clear of the inner end of the guide 11 and the valve 4 is free of the head 3 so as not to obstruct the passage of the air. When the valve 4 is seated loss of pressure through the stem 1 is prevented. This may be supplemented by the action of the part 9 closing against the inner end of the part 11. When it is required to relieve the inner pressure of the tube or other part the plunger is pressed inward thereby unseating the parts 9 and 4 whereby the confined air may readily escape through the stem 1.

It is observed that the opening in the plate 6 is in line with the opening of the stem 1 and that the free end of the spring 7 operates through the opening of the plate 6 and exerts a pressure on the valve 4 opposite and in line with the opening of the stem 1, there-

by causing the portion of the valve opposite the inner end of the stem to engage the same in a positive manner, whereby to prevent any loss of pressure. The plate 6 is resili-
5 ent and reinforces the valve 4 and serves to press the same upon its seat with a certain degree of pressure. The element 7 supplements the action of the part 6 and applies the pressure more directly to the valve 4 in
10 line with the opening of the stem 1, whereby to insure a positive and firm seating of the valve 4. When pressure is applied to the outer end of the plunger 8, it acts directly upon the free end of the spring 7, the ten-
15 sion of which is overcome, whereby the valve 4 may respond and open, thereby relieving the pressure to permit of quick deflation of the inner tube which is desirable at times, particularly to admit of compact folding
20 of the tube for carrying or storing.

Having thus described the invention, what I claim is:—

1. An air valve of the character specified comprising a tubular stem, a flap valve at the
25 inner end of the tubular stem and a plunger

passing through the tubular stem and adapt-
ed when pressed upon to unseat the valve at the inner end of the tubular stem whereby to relieve internal pressure.

2. An air valve of the character specified 30 comprising a tubular stem, a flap valve at the inner end of the tubular stem, a plate disposed exterior to the valve and having a central opening and a finger having its ex-
tremity extending through the opening of 35 the plate and engaging the valve.

3. A valve of the character specified com-
prising a tubular stem, a valve at the inner end of the stem, a spring actuated plunger 40 passing through the stem, a guide for the plunger within the outer portion of the stem, and a stop carried by the plunger and adapt-
ed to seat against the inner end of said guide.

In testimony whereof I affix my signature in presence of two witnesses.

STEVEN ^{his} X HOLICK.
